CLAIM

The ornamental design for a security release adapter for harness buckle, as shown and described.

DESCRIPTION

This application is related to U.S. Utility application Ser. No. 17/308,463 filed May 5, 2021.

FIG. 1 is a top left perspective view of a security release adapter for harness buckle, showing my new design;

FIG. 2 is a bottom right perspective view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a left elevation view thereof;

FIG. 8 is a right elevation view thereof;

FIG. 9 is a bottom perspective view thereof; shown with an enclosed buckle environment for clarity of disclosure; and,

FIG. 10 is a rear elevation view thereof; shown with an enclosed buckle environment for clarity of disclosure.

The broken lines in FIGS. 9 and 10, showing an enclosed buckle environment are for the purpose of illustrating environmental subject matter that forms no part of the claimed design.
